HOLDER FOR COLLAPSIBLE TUBES
AND THE LIKE

Reuben Gould, Jersey City, N. J.

Application July 10, 1933, Serial No. 679,597
Renewed December 28, 1934

2 Claims. (Cl. 248—20)

This invention relates to new and useful improvements in a collapsible tube and the like, holder.

The invention has for an object the construction of a holder which is adapted to be engaged upon the edge of a shelf or other similar article and which is provided with inturned parallel edges arranged to support a collapsible tube by the neck.

10 Still further the invention contemplates arranging the holder with a horizontal wall portion having a continuation at one end bent over the top to constitute a clamp for engaging a shelf, and also having continuations at the sides 15 for forming inturned edges adapted to engage heads of collapsible tubes.

Still further the invention contemplates the arrangement of a continuation at the other end of the horizontal wall mentioned in the previous 20 paragraph and formed to hold a safety razor or other similar article.

As another object of this invention an arrangement is proposed whereby one of the ends of the opposed edges for holding the heads of the collapsible tubes is closed so that the tubes may not 25 accidentally fall therefrom.

As another object of this invention an arrangement is proposed whereby the opposed sides are provided with a plurality of adjustable plates 30 adapted to engage against the necks of collapsible tubes of different diameters so as to be capable of supporting the tubes.

Still further the invention contemplates the construction of a holder provided with a clamping portion to engage the shelf and portions to support collapsible tubes by their necks.

As another object of this invention it is proposed to construct an article as mentioned which is simple and durable and which may be manufactured and sold at a reasonable cost.

40 For further comprehension of the invention, and of the objects and advantages thereof, reference will be had to the following description and accompanying drawing and to the appended 45 claims in which the various novel features of the invention are more particularly set forth.

In the accompanying drawing forming a material part of this disclosure:

Fig. 1 is a perspective view of a holder according to this invention.

Fig. 2 is a bottom view of Fig. 1.

Fig. 3 is a side elevational view of a holder according to a modification of the invention.

Fig. 4 is a bottom view of Fig. 3.

Fig. 5 is a side elevational view of another hold-

er constructed according to another embodiment of the invention.

Fig. 6 is a plan view of Fig. 5.

Fig. 7 is a transverse vertical sectional view taken on the line 7—7 of Fig. 6.

Fig. 8 is a view similar to Fig. 7 but illustrating a modified arrangement.

Fig. 9 is a plan view of Fig. 8.

Fig. 10 is a side elevational view of another holder constructed according to another modification of the invention.

Fig. 11 is a vertical sectional view taken on the line 11—11 of Fig. 10.

Fig. 12 is a fragmentary horizontal sectional view taken on the line 12—12 of Fig. 10.

Fig. 13 is a side elevational view of a holder constructed according to another embodiment of the invention.

Fig. 14 is a sectional view taken on the line 14—14 of Fig. 13.

5 The holder for collapsible tubes and razors according to this invention comprises a horizontal wall portion 10 having a continuation 11 at one end bent over and parallel therewith forming a clamp adapted to engage upon the edge of a shelf or similar article for the purpose of supporting the holder. Continuations 12 are arranged upon the sides of the horizontal wall portion 10 and have their edges directed towards each other forming a groove into which the head 13 of a collapsible tube 14 may engage. A continuation 15 from the other end of the horizontal wall portion 10 is disposed downwards and terminates in a horizontal portion 16 formed with a

25 cutout 17 in the free end. The fingers 18 formed by the cutout 17 have their ends 19 turned upwards. A safety razor 20 is adapted to be supported so as to have handle portions engaged downwards through the cutout 17 and the head of the razor resting upon the fingers 18.

30 The tubes 14 may be slipped free from the holder by moving them frontwards until the heads disengage from the opposed edges 12. The razor may be removed by first lifting it to a position in which it may be drawn rearwards to be removed from the holder. The downward directed continuation 15 is necessary in that a shelf supporting the holder engages in between the clamp portion 11 and the horizontal wall portion 10,

35 necessitating room for the insertion and removal of the razor.

40 In Figs. 3 and 4, a modified form of the invention has been disclosed which is very similar to the form illustrated in Figs. 1 and 2 except for the fact that it is not equipped with a razor hold-

ing portion. The corresponding parts of this holder may be recognized by the same reference numerals as those used in Figs. 1 and 2. The holder distinguishes from the previous holder in 5 the provision of a small continuation 18' from the free end of the horizontal wall 10 serving to close one end of the groove formed by the in-turned ends 12. This holder is adapted to be mounted upon the edge of a shelf and support 10 collapsible tubes by engaging the heads of the tubes into the grooves so that the opposed edges 12 engage the necks thereof.

In Figs. 5, 6 and 7 another modified form of the invention has been disclosed which is very 15 similar to the form illustrated in Figs. 3 and 4 except for the construction of the groove which supports the heads of the tubes. This form of the invention comprises a horizontal wall 21 having a continuation 22 at one end bent over and 20 parallel to the wall for forming a clamp to engage upon a shelf. The horizontal wall 21 is also formed with a central opening 23 which has the opposed sides constituting continuations 24 from material surrounding the opening. These 25 opposed sides 24 have their lower ends 25 directed towards each other. The rear end of the horizontal wall 21 has a downward continuation 21' serving to close the groove formed by the continuations 24 and 25.

In Figs. 8 and 9 another variation of the invention has been disclosed in which the holder is 30 very similar to the holder illustrated in Figs. 5, 6 and 7 except for the fact that the continuations 24 terminate in outturned edges 25'. In other 35 main respects the holder is identical, and for this reason a full view is thought not necessary. This holder is equipped with a top continuation forming a clamp for which it may be engaged upon the edge of a shelf. A plurality of plates 26 are 40 arranged in edge contacting relation with each other and are transversely adjustably mounted upon the portions 25'. These plates 26 are formed with transverse slots 27 engaged by rivets 28 engaging through the slots and mounted upon the 45 portions 25' so that the plates 26 are slidably mounted transversely.

A spring 29 is provided for each of the plates 50 and is mounted upon the under side of the horizontal wall 21 and engages the outer edges of the plates so as to normally urge the plates inwards. The plates 26 form the supports for the 55 head of the collapsible tube to support the tube. The tubes may be engaged upon the plates from the end similar to the engagement of the tubes according to the form of the invention illustrated in Figs. 5-7 inclusive. The plates 26 are 60 adapted to accommodate the necks of tubes of different sizes. Springs 29 hold the plates 26 to accommodate the small necks and if the tubes have larger necks the plates may be manually 65 forced outwards. It must clearly be understood that the slidably mounted plates 26 and the resilient springs 29 may be associated with any of the forms of this invention illustrated in the previous mentioned figures.

In Figs. 10-12 inclusive another modified ar-

5 arrangement has been disclosed in which the holder comprises a horizontal top wall 30 having a continuation 31 at one side bent therefrom and forming a clamp to support the holder. Other continuations 32 from the sides are first bent towards each other until they meet and then downwards along the areas 33 and terminate in horizontal portions 34 extended away from each other. These horizontal portions have a plurality of 10 openings 35 communicating with the edges adapted to receive the necks of the tubes in a manner so that the heads are disposed above the portions 34 and so support the tubes. A feature of this construction lies in the fact that the transverse cross section of the holder is substantially 15 that of an I beam, see Fig. 11, which is a strong structural shape and therefore the holder may be constructed from thin metal and still have great strength.

In Figs. 13 and 14, another variation of the invention has been disclosed in which the holder 20 comprises a horizontal wall portion 36 having a continuation 37 at one end extended thereover and forming a clamp for mounting the holder upon the edge of a shelf and having another continuation 38 at one side only terminating in a horizontal continuation 39 extended beneath the horizontal wall 36. The portion 39 is provided with several edge cutouts 40 adapted to receive the heads are disposed above the portion 39 and so support the tubes.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I 40 claim as new, and desire to secure by United States Letters Patent is:—

1. In a tube and the like holder, a horizontal wall, spaced continuations from said horizontal wall, a plurality of plates in opposed rows and transversely slidably mounted on said spaced continuations presenting opposed edges to each other for forming substantially a groove for receiving and holding the heads of collapsible tubes, and resilient means urging said plates towards each other.

2. In a holder of the class described, a horizontal wall having a central longitudinal opening with the material at the sides of the opening continued downwards and associated with elements 55 extended towards each other forming a groove for supporting the heads of collapsible tubes to support the tubes, a continuation from the other end of said wall serving to close one end of said groove, said elements comprising a plurality of plates in opposed rows and transversely slidably mounted on the material at the sides of said opening, and resilient means urging said opposed elements together.
